UNITED STATES PATENT OFFICE.

JOHN THOMSON, OF NEW YORK, N. Y., ASSIGNOR TO JOHN THOMSON PRESS COMPANY, OF JERSEY CITY, NEW JERSEY, A CORPORATION OF NEW JERSEY.

PRINTING-PRESS.

1,113,508.

Specification of Letters Patent.

Patented Oct. 13, 1914.

Application filed December 14, 1910. Serial No. 597,260.

To all whom it may concern:

Be it known that I, JOHN THOMSON, a citizen of the United States, and a resident of the borough of Manhattan of the city of New York, in the State of New York, have invented certain new and useful Improvements in Printing-Presses, of which the following is a specification, reference being had to the accompanying drawing, forming a part hereof.

This invention relates to printing presses in which none of the reciprocating form inking rollers will pass in contact with the form in more than one direction of its reciprocatory travel during each printing period. In the specific embodiment of the invention illustrated upon the drawing all of the form inking rollers pass in contact with the form in one direction of reciprocation but not in contact with the form in the reverse direction of movement.

While the inking device is applicable to many types of presses, the application, for the purpose of the present description, is to be understood as being applied to a style of platen printing press generally known to the trade as "The Colt's Armory."

In the drawings, Figure 1 is a diagrammatic illustration of the action; Fig. 2 is a detached view of a carriage-way with the trucks or roller wheels, and Fig. 3 is a detached view of a form-roller with its trucks thereon.

Complete details have been omitted from the drawings for the reason that there are many thousands of these presses in operation with which printers and mechanicians skilled in the art are familiar. Thus, A is one of the two frames, tied together by rods, as 2, this structure constituting the carriage and in which are mounted a series of slideable boxes, B, usually from two to four, the latter number being here shown. In these boxes the composition form inking rollers C are mounted, as by their stock-spindles, 3. Attached to each box is a spindle, as 4, freely mounted in the frame, which carries a spiral spring, as 5, acting to pull the box inwardly, or to the right hand side of the drawing. Thus, when the boxes are drawn outwardly the form rollers may readily be inserted or removed and the said rollers are thereby free to rise and fall, if needs be, against and with the resilient action of the springs. The carriage, as a whole, is mounted in car-

riage ways, as R, Fig. 2, bolted to the side of the bed of the press, to traverse down and up, the action being produced by links, as D, connected to and actuated by vibrating arms. When the carriage is fully up a fresh charge of ink is delivered to the form rollers by a revolving cylinder, or cylinders, as denoted by the broken lines, H.

All of the foregoing is old and well known in the art, and it has also been the practice for thirty years past, in the instance of the aforesaid "Colt's Armory" press, to apply latches to the carriage whereby one or two of the form rollers would be carried out, free from the form, on the down movement; but would be released at or near the lower termination of the action, the suspended roller or rollers then being free to ink the form, together with the other rollers not primarily suspended, on the up-movement. The conditions embodied in the device referred to has given and will give good results when used in connection with ordinary type-forms; but with certain half-tones, three-color and tint-plates, and the much finer and denser inks now being produced, it frequently fails to realize that degree of perfection which is essential to the highest grade and quantity of product. Consequently, practice under new and more severe conditions has demonstrated that the earlier theory does not hold good, i. e., to ink the form from the top downwardly with a portion of the rollers and from the bottom upwardly with all of the rollers.

It has been found after much experimentation, and abundantly proven upon a commercial scale of operation, that the desired result can be obtained by simply causing all of the form rollers to pass in contact over the form once. Without pretending to give a complete analysis of the reasons why this result should ensue—for it is somewhat contradictory of the usual opinion—this much, however, can be said, namely: that with many inks the "body" or character is such that when once deposited as a film upon the form if the same roller section or sections which have already engaged the form again pass over it during the same printing period a portion, or portions, of the primary film is again "picked up," or withdrawn.

The improved method of operation has been realized in the manner now to be described.

The outer surfaces of the boxes, B, project somewhat beyond the finished face, as 7, of the carriage frame. Pivoted on each frame, as at 8, 9, are two arms, 10, 12, and 5 to the inner ends of these arms a connecting link, 13, is also pivoted, as at 14, 15. The connecting links lie against the finished surfaces of the frames, their rearward position being limited by stops, as the pin 16 10 with which arm 10 engages.

Now, when the parts are in the full-line position shown in the drawing, all of the form rollers will ink the form J on the down movement, as indicated at K; but as the 15 carriage nears the lower termination of its movement the extension, 10^a, of the arm 10, is caused to impinge upon a projection or pin, as 17, fixed in the side frame of the press, so as to force the end, 10^a, upwardly 20 until the arms lie about horizontally, as 18. That is, the swinging pivots, 14, 15, are carried to the points 19, 20, which thus carries the link forward and forces out all of the boxes. This, then, leaves all of the rollers 25 suspended free, as denoted at P, so that on the return or up-movement they will not be in contact with the form. The rollers are thus returned until they are nearing the cylinders when the extension, 10^a impinges 30 upon a projection or pin as 22, mounted in the carriage-way of the press, and when the pivots 14, 15, are carried slightly beyond their dead centers they will be snapped by the reaction of the boxes, to the full line 35 position of the drawing.

It is to be noted that the connecting link may engage pins set into the faces of the boxes when such a construction is more convenient than that described.

40 In previous practice the lower roller or the two lower rollers, have been latched out by the action of the main cylinders, the latch simply acting to hold them in such position until relieved at the bottom of the 45 stroke; but in the present device this condition is reversed, the rollers being forced out by the swing of the carriage at or near the termination of the down movement. The advantages of this reversal of the 50 conditions are that rollers pass from the cylinders directly to the form; there is less liability of slippage between the roller trucks, as S, and the ways, as R, and the snap of the release is cushioned by the contact of the 55 composition rollers upon the cylinders. Moreover, no springs are required nor are any close adjustments necessary, such as providing for the whip-like variation in the reversal of the carriage at high rates of speed, especially when the connections become worn.

The device as herein described and illus-

trated operates with the utmost smoothness of action and is practically noiseless and not only can far better results be obtained by 65 this method of single rolling but the output is in many classes of forms easily doubled.

I claim as my invention:

1. In a press the combination of a frame provided with ways and carrying means to 70 deliver ink to an inking mechanism, a form and a roller inking mechanism comprising inking rollers provided with trucks, which inking mechanism is arranged to be reciprocated between the position for receiving ink from the ink delivering means and the position for inking the form, the rollers in the inking mechanism all mounted so that the trucks thereof will be rotated due to their engagement with the ways during 75 the travel from the means to deliver ink to the inking mechanism, the rollers also mounted so that they will contact with the form only during the travel from the position in which they receive ink from the ink 80 delivering means and so that they will be elevated in a manner to prevent their contacting with the form during any return movement over the form and means between the frame and rollers for causing said 85 elevation of the rollers.

2. In a press a frame having carriage-ways and carrying a vertical form, a vertical reciprocating roller inking mechanism having all the rollers therein provided with 90 trucks, said rollers being supported so as to ink the form on the downward stroke of the inking mechanism, and means to elevate all of the rollers prior to the return movement of the rollers over the form 100 whereby the latter will not receive any ink during the upward stroke, the rollers being rotated on the downward stroke, prior to the engagement of the rollers with the form, due to the engagement of the roller trucks 105 with the ways.

3. In a press a frame carrying means to deliver ink to an inking mechanism, a vertical form, a reciprocatory mechanism having inking rollers provided with trucks 110 which travel on ways in the press, the rollers being rotated by the trucks on the ways when the inking mechanism is traveling forward toward the form from the means which delivers ink to the inking mechanism, 115 and means for lifting the rollers from contact with the form when the inking mechanism is returning.

This specification signed and witnessed this 12th day of December, A. D., 1910.

JOHN THOMSON.
